UNITED STATES PATENT OFFICE.

WILLIAM J. STEERE, OF ROCKWOOD, TENNESSEE, ASSIGNOR TO SOUTHERN TEXTILE MACHINERY COMPANY, OF PADUCAH, KENTUCKY, A CORPORATION OF KENTUCKY.

SEWING MACHINE.

Application filed December 15, 1923. Serial No. 680,900.

This invention relates to machines for uniting fabrics, and which comprises, generally, a rotatable dial having a series of radially extending impaling pins for receiving and advancing the edges of the fabric to be united, and a sewing mechanism including a needle and a looper acting in conjunction with each other to effect the sewing operation while the edges of the fabric are advanced by the impaling pins.

An object of the invention is to provide an attachment for a machine of the type disclosed in the patent to Keyser, 1,069,336, granted August 5, 1913. The attachment is intended to modify the operation of such a machine by causing the dial carrying the fabrics to be continuously rotated and effecting lateral movement of the thread needle and, preferably, also of the looper, while the needle is in the loops to correspond with the movement of the subjacent impaling pins.

A further object of the invention is to provide a mechanism for laterally moving the needle and looper which may be readily applied to the machine, and which is also adjustable to vary the extent of lateral movement imparted to the needle and looper.

Further objects of the invention, such as to provide a novel, simple and efficient construction and organization of mechanism for actuation of the needle and looper during the sewing operation, will become apparent as the description proceeds in connection with the embodiment of the invention disclosed in the accompanying drawings, wherein,

Figure 1 is a top plan view of the machine, showing the invention applied thereto.

Figure 2 is a rear elevational view.

Figure 3 is a front elevational view of portion of the sewing mechanism.

Figure 4 is an end view of the sewing mechanism.

Figure 5 is a cross section through the driving shaft on substantially the line 5—5 of Figure 2.

Figure 6 is a sectional detail view of the cam for moving the sewing mechanism laterally as it is operated.

Referring to the drawings for a more detailed description, the machine shown in the drawings is of standard type, similar to that shown in the patent referred to, and its main frame comprises a bed plate 4 and an

overhanging arm 8 extending upwardly therefrom. Journalled at the outer end of the arm and supported thereby is a rotatable dial 9 carrying a ring of radially extending impaling pins 10. The dial is driven continuously from a main shaft 11 mounted in a bearing 12 in the arm 8 and in a bearing 13 extending upwardly from the bed plate. The shaft carries a bevel gear 14 meshing with a bevel gear 15 upon a shaft 16, the latter having fixedly positioned thereon a worm 17 meshing with a worm gear 18, from which the dial is driven. Further description of this mechanism for imparting continuous rotation to the dial is thought to be unnecessary, since the same is old and well known in the art and being shown, for instance, in the patent to Wright, 1,057,106, March 25, 1913. It will be noted, however, that the end of the shaft 16 adjacent the main driving shaft is supported in a bracket 20, which extends upwardly and is carried by a bracket supporting plate 21 fixedly secured upon a stationary rod 22 extending through the arm 8 and rigidly mounted thereon. The rod 22 serves as a support for the sewing mechanism, and for this purpose carries a bracket 23 having a sleeve portion 23' surrounding the rod. The bracket has a depending arm 24 provided with a boss 25, which is straddled by the forked end 26 of a guide 27, the latter at its upper end being fixedly secured to the rod 22. For this purpose, the end of the guide is split, as at 28 (Figure 4), to surround the rod and carries a clamping screw 29, by means of which the guide is secured to the rod. This guide serves to maintain the bracket against rocking movement upon the rod 22, but permits a sliding movement of the same longitudinally upon the rod, as will later be described. In the lower end of the guide is mounted an adjusting screw 30, which abuts the side of the boss 25 and maintains the bracket in vertical position.

The bracket 23 has an additional depending arm 31 (Figures 2 and 3), having at its lower end a boss 32, which serves as a vertical bearing for a rock shaft 33, the latter carrying at its lower end a looper arm 34, upon which is mounted a curved looper 35. The rock shaft 33 is rocked to oscillate the looper by mechanism which will later be described. A shaft 36 extends through the boss 25 and into a side opening (not shown) in the boss 32 so that the same is

bodily carried by the bracket 23 and may move laterally with the bracket. Upon the shaft 36 is mounted a sleeve 37 having formed integrally therewith a radially extending needle arm 38 (Figure 3) and a crank arm 39. The needle arm serves as a support for a curved thread needle 40, which is adapted to be oscillated in a vertical plane by mechanism which oscillates the sleeve 37 through the crank arm 39. It will be understood that as the needle is oscillated in a vertical plane to carry the same adjacent the pins, the looper is oscillated in a horizontal plane substantially paralleling the plane of the impaling pins. That is to say, the eye of the needle during the operation thereof describes a vertical arc and the eye of the looper during the oscillation thereof moves from side to side of the line of sewing 20 scribing an arc in a single plane at an angle with respect to the plane of the arc described by the needle eye. The vertical shaft 33 serves as an axis for the looper, while the horizontal shaft 36 serves as an axis for the 25 oscillatory movement of the needle, both of the shafts being carried by the bracket 23. The invention includes means for moving the bracket 23 longitudinally on the rod 22, so that the needle is carried laterally while between the loops to correspond with the movement of the subjacent impaling pins. This 30 actuating mechanism will now be described.

Upon the main shaft 11 is fixedly secured a disc 40 carrying upon one face a cam ring 35 41, shown more clearly in Figures 1 and 6. Screws 42 extending through the face of the ring secure the same upon the disc, and adjusting screws 43 passing through the disc will serve to adjust the ring toward and 40 from the face of the former, whereby the extent of lateral movement of the bracket may be varied. A follower 44 engages the face of the cam and is mounted upon a reciprocable push rod 45 having a slide bearing 45 in a sleeve 46 secured in a bracket 47 extending rearwardly and upwardly from the rod 22. The opposite end of the push rod carries a forwardly extending arm 48 (Fig. 4), in which is mounted a finger 49 50 paralleling the push rod 45 and bearing against an arm 50, extending upwardly from the bracket 23. The follower 44 is normally maintained in contact with the cam by means of a tension spring 51 anchored at 52 to a pin upon the bracket 47, and at its opposite end secured to a pin 53 upon the follower; the spring serves to return the rod to the right, as viewed in Figure 2, when, under the actuation of the cam, 55 it has been moved to the left. It will be understood that as the cam rotates, the follower and push rod are moved to the left (Figure 2), and the finger 49 bearing upon the arm 50 of the bracket moves the latter 60 with the push rod, thus imparting a lateral

movement to the looper and thread needle which are supported by the bracket. The bracket 23 is returned to the position shown in Figures 2 and 3 by means of a spring 54 (Figure 3) anchored at 55 to the guide 27 and having its other end secured to a lug 56 upon the bracket. When the bracket is moved by the cam to impart lateral movement to the needle, the spring 54 is placed under tension and continued rotation of the cam permits the spring to return the bracket to its normal position, the return movement being limited by a collar 57 fixedly mounted upon the rod 22 and serving as an abutment for the sleeve portion of the bracket. It is often desirable to vary the extent of the lateral movement of the needle, as for instance when the number of dial pins to the inch is varied, which is sometimes done to take care of a change to coarser or finer fabrics. The cam ring 41 upon the plate 40 may be adjusted for this purpose by releasing the screws 42 and rotating the adjusting screws 43 to carry the ring toward or away from the face of the plate; thus rendering unnecessary the provision of a new cam.

The mechanism for operating the needle and looper will now be described. For oscillating the looper 35, the main shaft 11 is connected to the vertical looper shaft 33 by means of a pitman 60 connected at one end to a strap 61 surrounding an eccentric 62 upon the main shaft. As in the patent to Keyser referred to, the outer surface of the eccentric is made convex and the inner surface of the strap concave to permit the pitman to be rocked laterally as the bracket 23 is moved laterally. At its opposite end, the pitman is connected to an arm 63 fixedly secured to the looper shaft 33. No detailed description of this connection is thought necessary, since it does not constitute a part of the present invention and corresponds precisely to the connection shown in the patent to Keyser already mentioned. It will be noted, however, that the arm 63 upon the looper shaft supports an upwardly extending post 64 (Figure 4), the upper end of which is provided with a ball 65 fitting into a socket in the pitman.

The thread needle 40 is oscillated in a vertical plane from a crank pin 67 (Figure 1) at the end of the main shaft, to which is secured a pitman 68 connected at its other end to a pin 69 fixedly secured in the crank arm 39 on the needle sleeve 37. The crank pin 69 extends through an eye 70 at the outer end of the pitman and is of sufficient length to permit the needle sleeve and the pin to move laterally relative to the pitman 68. The latter is held rigidly against lateral movement with the needle supporting bracket by means of a peripherally grooved wheel 72 upon the crank pin 67, into the

groove of which projects a stud 73 secured to the pitman by means of a bracket 74. The stud and bracket are rigidly connected to the pitman, and since the former projects into the grooved wheel, the pitman is held rigidly against lateral movement with the needle supporting bracket. When the bracket has moved laterally, the crank pin 69 upon the needle support reciprocates in 10 the eye 70 at the outer end of the pitman.

During the operation of the machine, the fabric to be united is supported upon the impaling pins and is advanced during the continuous rotation of the dial to the sewing mechanism. As the driving shaft is operated, either by means of a hand crank C at the outer end of the same, or by means of power applied to the driving pulley P, the needle is oscillated in a vertical plane, while the 20 looper is oscillated in a plane at an angle with respect to the plane of the needle. The eye of the looper moves from side to side of the line of sewing and describes an arc in a plane paralleling the plane of the 25 ring of the impaling pins. While the needle is in its extreme downward position, it is moved laterally by the mechanism already described, so that it corresponds with the movement of the dial, and when it has 30 moved from adjacent the impaling pins, it is returned by means of the spring 54 to the position shown in Figures 2 and 3.

Since the invention relates entirely to the attachment including the parts which afford 35 a lateral movement to the needle support, no detailed description of the usual sewing operation is thought necessary.

The needle and looper of the machine to 40 which the invention is shown as applied, perform the sewing operation in the same manner as the machine disclosed in the patent to Keyser referred to, while the invention adapts the machine to the continuous rotation of the dial by moving the needle 45 and looper laterally while the former is adjacent the impaling pins.

It being understood that the invention is not limited in its application to the particu-

lar machine illustrated and described in detail, but may be applied to other types of 50 machines, what I claim is:

1. In a machine for uniting fabrics, the combination with a continuously rotating dial having a ring of impaling pins, a driving shaft, a curved thread needle, a supporting arm for said needle, means for oscillating said arm to carry the needle adjacent the pins, a looper, a bracket carrying said needle, means for moving said bracket laterally to impart a lateral movement to 60 the needle during its oscillatory movement whereby the same is carried laterally while in the loops to correspond with the movement of the subjacent impaling pins, said last mentioned means being actuated from the driving shaft, and including a cam driven from the driving shaft, means connecting said cam with the bracket, and means for adjusting the cam to vary the extent of the lateral movement of said 70 bracket.

2. In a machine for uniting fabrics, the combination of a dial having a ring of impaling pins, means for continuously rotating the dial, a bracket, a support for said 75 bracket upon which it is longitudinally movable, a driving shaft, a cam driven from said shaft, a follower for said cam, a push rod carrying said follower, and means on said rod engaging the bracket whereby the 80 latter is moved on its support by said cam, a thread needle carried by said bracket, means for oscillating the needle on said bracket, a looper, a looper support on said bracket, means for oscillating said looper 85 support in a plane at an angle to the plane of movement of said needle, said bracket moving laterally during the oscillation of the needle whereby the latter is carried laterally while in the loops to correspond with 90 the movement of the subjacent impaling pins, and means for varying the extent of lateral movement of the bracket.

In testimony whereof I have hereunto set my hand.

WILLIAM J. STEERE.
